UNITED STATES PATENT OFFICE.

HENRY M. KEITH, OF WEST FRANKFORT, ILLINOIS.

BRUSHING MACHINE.

Application filed March 27, 1922. Serial No. 547,052.

To all whom it may concern:

Be it known that I, HENRY M. KEITH, a citizen of the United States, residing at West Frankfort, in the county of Franklin and State of Illinois, have invented new and useful Improvements in Brushing Machines, of which the following is a specification.

This invention contemplates the provision of a power operated brushing machine, which is designed to brush the clothes and shoes of the user, when he occupies a position upon the platform of the machine, the latter being controlled by a suitable switch.

One of the chief characteristics of the present invention resides in providing a machine with a brush of spiral formation which is utilized to brush the clothing, directing the foreign matter into a casing, from which it is forced into a suitable receptacle by means of a fan.

Another object of importance resides in the provision of a brush of the above mentioned character, susceptible of being lengthened or shortened to meet all requirements, and associated with means for automatically taking up the slack incident to the shortening of the brush.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a front elevation.

Figure 2 is a side elevation, partly in section.

Figure 3 is a horizontal sectional view taken on line 3—3 of Figure 2.

Figure 4 is an enlarged detail view of the locking means and one of the brush disks.

Figure 5 is a plan view of one of the disks, partly in section, showing the association of the spring with the brush shaft.

Figure 6 is an enlarged fragmentary view, partly in section of the lower portion of the brush and its associated parts.

Referring to the drawings in detail, 10 indicates a platform which is preferably of hollow formation, and which may be constructed of any suitable material and design without departing from the spirit of the in-

vention. Rising from the platform adjacent one end thereof, is a casing 11 open at one side and through which opening the brush operates for the purpose of brushing the 60 clothes of the user.

Journalized between the platform 10 and the top 12 of said casing is the shaft 13 which has spirally wound about the same, a brush indicated at 14. The brush is of a flexible character, and is terminally connected to disks 15 and 16 respectively. The disk 15 is loosely mounted upon the shaft 13, while the disk 16 is held fixed relatively to the shaft by means of a locking element 17. 65 This locking element is pivoted as at 18 on the adjacent disk and has a forked extremity 19 which slides in a groove 20 formed in the shaft 13. One end of this forked extremity is adapted to be received by one of a plurality of openings 21 provided in said shaft to hold the disk 16 fixed relatively to the latter, a spring 22 exerting a pressure upon the locking element to hold it in this position. It is of course understood that the 70 disk 16 is susceptible of longitudinal sliding movement on the shaft 13 for the purpose of lengthening or shortening the brush as the occasion may require, and this can be 75 readily accomplished by depressing upon the locking element to move said forked extremity out of said openings, and subsequently releasing said locking element to permit it to assume its active position, and thereby hold the disk 16 at any desired position upon the shaft. The disk 15 which is loosely mounted upon the shaft has associated therewith a resilient element 23 of any suitable construction, this element being utilized to wind the surplus portion of the 80 brush about said stick, thereby taking up the slack. The resilient element 23 tends to rotate the disk 15 in this direction, and thereby take up the slack, should the brush 85 become slack from any cause whatever.

The bristles of the brush are arranged diagonally as illustrated so as to brush downwardly, and thereby direct the dirt and dust from the clothing in a direction of the casing 11. The base or platform 10 immediately beneath the casing 11 is slotted so that this foreign matter can find its way into the hollow base 10, it being subsequently removed therefrom in a manner to be hereinafter described. Arranged beneath the 90 disk 15 is a circular brush 24 which is fixed upon the shaft 13 for rotation therewith, 95

and this brush is utilized for cleaning the shoes, when the user occupies a position upon the base or platform 10 in juxtaposition to the brushes above referred to. Arranged within the casing 11 is a strap 26 from which teeth 27 project, and these teeth are disposed to clean the brush 14 incident to the rotation of the shaft 13. Any suitable means may be utilized for rotating the shaft 13, but I preferably make use of an electric motor indicated at 27, the shaft 28 of which is journaled in suitable bearings 29. This motor is arranged within the hollow base 10, and carried by the shaft 28 is 10 a disk 30 which is arranged at a right angle to the disk 31 carried by the adjacent end of the shaft 13, thereby providing a friction drive for the shaft 13. One end of the hollow base 10 is provided with an opening, 15 through which communication is had between the said hollow base and a sack or other suitable receptacle 32, and the dirt, dust and other foreign matter is forced from the hollow base 10 into the sack 32 20 through the instrumentality of a fan 33 carried by the motor shaft 28. Any suitable switch may be used to control the motor, and this switch is indicated generally at 34. The machine is simple in construction, and efficient in operation for the purpose intended, 25 and can be used to advantage in hotels, barber shops, and other places.

While it is believed that from the foregoing description, the nature and advantages 30 of the invention will be readily apparent, I desire to have it understood that I do not limit myself to what is herein shown and described, and that such changes may be resorted to when desired as fall within the 35 scope of what is claimed.

What I claim is:—

1. A machine of the character described comprising a base, a casing rising therefrom and open at one side, a rotatable shaft operating in said casing, means for rotating said shaft, and a spiral brush carried by said shaft and projecting beyond said casing through the open side thereof for the purpose specified.
2. A machine of the character described comprising a base, a casing rising therefrom and open at one side, a rotatable shaft operating in said casing, a flexible brush wound spirally about said shaft, and means for rotating said shaft for the purpose specified.
3. A machine of the character described

comprising a base, a casing rising therefrom and open at one side, a rotatable shaft operating in said casing, a flexible brush wound spirally about said shaft, means whereby said brush may be lengthened or shortened, means for taking up the slack incident to the shortening of the brush, and means for rotating said shaft.

4. A machine of the character described comprising a base, a casing rising therefrom and open at one side, a rotatable shaft operating in said casing, a spiral brush supported by said shaft, a circular brush supported by said shaft below said spiral brush, and means for rotating said shaft.

5. A machine of the character described comprising a base, a casing rising therefrom and open at one side, a rotatable shaft operating in said casing, spaced disks associated with said shaft, one of said disks being loosely mounted upon the shaft, the other of said disks being slidably mounted on said shaft, means for holding the second mentioned disk fixed relatively to the shaft in a given position, a flexible brush terminally connected with said disks and wound spirally about said shaft, means for turning said loosely mounted disk independently of the shaft to take up the slack of said brush, and means for rotating said shaft.

6. A machine of the character described comprising a base, a casing rising therefrom and open at one side, a rotatable shaft operating in said casing, a motor, a driving connection between the motor and said shaft, a spiral brush supported by the shaft, a circular brush supported by the shaft adjacent the base, and a cleaning element for said brush arranged within the casing and secured thereto.

7. A machine of the character described comprising a hollow base, a casing supported thereon and open at one side, a rotatable shaft operating in the casing, a motor arranged within the hollow base, a driving connection between the motor and said shaft, a spiral brush supported by the shaft, a circular brush supported by the shaft adjacent the base, said casing communicating with the hollow base to deposit the dirt in the latter, a receptacle communicating with the base, and a fan operating to force the dirt from the base to said receptacle.

In testimony whereof I affix my signature.

HENRY M. KEITH.
